BELT BUCKLE

Oscar Katzman, Los Angeles, Calif., assignor to
 Hickok Manufacturing Company, Inc., Rochester, N. Y., a corporation of New York

Application April 15, 1949, Serial No. 87,642

6 Claims. (Cl. 24—191)

1

This invention relates to fasteners and more specifically contemplates belt buckles, ornamental pins and the like commonly used to display initials.

Belt buckles adapted to carry the initials of the wearer have long met with popular favor. However, to provide each retailer with a stock of buckles sufficient to meet the demand for any combination of initials requires that the individual letter elements be structurally separate from one another as well as from the belt-engaging members, and further, that the parts be susceptible to assembly with the letter elements in any desired serial arrangement. Accordingly, buckles have been devised which consist essentially of a frame, carrying the belt-engaging members, equipped with guide rails between which the letter elements may be inserted. In many instances the frame and guide rails detract from the ornamental effect of the initials.

It is a principal object of the present invention to provide a buckle comprising belt-engaging members in combination with means for supporting a plurality of structurally separate letter elements in any prearranged sequence, in which the belt attaching members and letter element-supporting expedients are entirely hidden from view when the buckle is in use.

Another object is to provide a buckle of the character above referred to wherein the belt forms a complete background for the letters.

More specifically, it is an object hereof to provide a fastener for securing a series of ornamental elements in predetermined juxtaposition, to a device for attaching the assembly to wearing apparel, comprising a flat-loop retainer upon which the ornamental elements may be threaded, in combination with means for directly but releasably connecting the last-assembled element to the retainer so as to prevent inadvertent displacement of any of the elements.

Still another object is the provision of ornamental elements adapted to be assembled in serial arrangement and secured in adjusted relationship by the mechanism above referred to, comprising an ornamental face and a pair of channel members rigidly connected to the upper and lower edges respectively, of the face, to encompass the supporting structure for the ornamental elements.

Other objects and salient features of my invention, such for example as, simplicity of construction, economy of manufacture, ease of assembly, attractive appearance, and durability will be apparent from the following description read in

2

the light of the accompanying drawings, in which:

Fig. 1 is a front elevation of a buckle embodying my invention;

5 Fig. 2 is a top edge view of the assembly shown in Fig. 1 part being broken away;

Fig. 3 is a rear elevation of the assembled buckle;

10 Fig. 4 is an enlarged elevation of the pin assembly for releasably securing the various parts together;

Fig. 5 is a sectional view taken substantially along the plane of line 5—5 of Figure 3;

15 Fig. 6 is an elevation of the open end of the retainer loop member upon which the letter elements are assembled;

Fig. 7 is a back elevation of the retainer loop member;

20 Fig. 8 is a top edge view of the said member;

Fig. 9 is an end elevation of one of the letter elements;

Fig. 10 is a back elevation of the letter element shown in Fig. 9.

Referring to the drawings more in detail, the 25 numerals of which indicate similar parts throughout the several views, 15 designates a rear retainer member comprising a strip of metal doubled upon itself to form a pair of parallel, flat reaches or sections 16 and 17 connected together by a bight portion providing an abutment stop.

30 The front section 16 of the retainer 15 is of a width slightly greater than that of the belt to be used therewith. Projecting forwardly from each of the upper and lower edges at the side portions 38 and 40 and terminating beyond the end portions 42 and 44 of the front section 16 of the retainer are a pair of side flanges 18 which with the section 16 form a channel in which the belt free end (not shown) to be engaged, is accommodated. The back section 17 of the retainer 35 is narrower than the front section 16 and its free end is equipped with a pair of integral vertically-aligned eyes 19 which project rearwardly in vertically-spaced relationship (see Fig. 6) for a purpose hereinafter more in detail described.

40 The letter elements 20 and 21 bearing, in the embodiment depicted, the letter "O," and the letter "K," respectively, each comprise a face plate 22 stamped or otherwise cut in the form of a block letter. The letter elements are all of the same width and height, the latter dimension being slightly greater than the vertical dimension of the front section 16 of the retainer 15. Extending across the back of the face plate 22 45 of each letter element is a rear member or back

55

panel 23, secured in spaced relationship with the face plate 22 by integral side flanges 24 at its upper and lower edges, respectively. The foremost edges of the respective flanges 24 are formed with inwardly directed rails 25, each of which is of a width substantially equal to or slightly greater than the thickness of the flanges 18 of front section 16 of the retainer, for a purpose later made apparent. The rails 25 extend the full width of the letter element, as is indicated in the letter element 21 in Fig. 1, and accordingly the rails are visible from the front of those letter elements in which the upper or the lower marginal edge of the face plate 22 is interrupted. The letter elements 20 and 21 are assembled upon the retainer in the order in which they are to be read, the first letter element 20 being slipped over the front section 16 of the retainer with the back panel 23 between the sections 16 and 17 and in abutting relation with the abutment stop at the fold portion of the retainer at which the front and back sections 16 and 17 are joined. The lateral edges of the back panel 23 of each letter element 20 and 21 are recessed as at 26 to permit the letter element to overhang and completely hide the end of the retainer 15 so engaged.

The specific embodiment illustrated is adapted for the assembly of two letter elements. By varying the dimensions of the several parts in a manner which will be obvious, the individual letter elements may be of any length desired and the supporting structure may be adapted to carry, in operative relationship, a single letter element or any desired number thereof.

The second letter element 21 is similarly slid over the unattached end of the front section 16 of the retainer, being moved into abutting relationship with the letter element 20 first installed. The top and bottom marginal edges of the panel 23 as well as the flanges 24 and rails 25 of each letter element are slightly wider than the face plate 22 and accordingly contact the corresponding parts of the other letter element when assembled on the retainer so as to hold the face plates 22 of the respective letter elements in slightly spaced relationship, as indicated in Fig. 1. With the letter elements 20 and 21 installed on the rear retainer 15, the flanges 18 of the front section 16 of the retainer will contact the inner surfaces of the flanges 24 of the letter elements and will be engaged between the upper and lower marginal edges, respectively, of the back panels 23 and the opposed rails 25 which are secured to the backs of the face plates 22 of the letter elements. From the foregoing description of the means to attachably connect the side flanges 24 to the side portions of the rear member, it will be observed that the flanges 18 of the section 16 of the retainer 15 will be completely hidden by the rails 25 when the buckle is in use, as seen in Fig. 1. Furthermore, the letter face plates 22, flanges 18 and section 16 will define a passage for the free end of a belt to be received therein.

Each of the letter elements is provided with a pair of eyes or apertured ears 27 attached rigidly to the upper and lower marginal edges of the back panel 23 thereof adjacent the side of the letter element which, when assembled with the retainer, lies nearest adjacent the eyes 19 of the retainer. The eyes or apertured ears 27 are spaced apart a distance slightly greater than the distance between the eyes 19 of the retainer so as to encompass the latter upon assembly and assume positions axially-aligned therewith.

In order to connect the ends of the belt with

which the buckle is to be used, I provide an eccentric locking device comprising a tubular member 28 of a length adapted to fit between the eyes 19 of the retainer 15. Projecting from one side 5 of the tubular member 28 is a triangularly-shaped bail 29 with which one end of the belt, equipped with snaps or the like, is permanently engaged, in a conventional manner. To releasably secure the opposite or free end of the belt an eccentric friction grip 30 is integrally formed on one side of the tubular member 28. The eccentric grip 30 has a surface portion longitudinally ribbed as at 31 to augment the tenacity of the frictional engagement of the locking device with the belt end, 10 when the eccentric grip is pivoted into its position for clamping the belt against the face plate of the display member. The side of the tubular member 28 opposite to the ribbed surface is formed with an elongated slot 32 out of which a 15 pair of finger grips 33 extend. The finger grips are secured to the inner ends of a pair of pins 34, respectively, slidably in the bore of the member 28. The pins 34 are normally projected from opposite ends of the bore of the tubular member by a spring 35 within the bore and interposed between the inner ends of the pins 34. The belt-engaging friction grip 30 and bail 29 assembly 20 may be pivotally engaged with the retainer and second assembled letter element 21 by contracting the finger grips 33 so as to withdraw the ends of the pins 34 into the bore of the tubular member 28, inserting the latter into alignment with the eyes 19 and 21 of the retainer and second letter element 21, and thereupon releasing the pins 34 which will be projected through the aligned eyes by the spring 35. By thus locking the second letter element 21 to the retainer 15, the letter element so engaged prevents withdrawal of the first assembled letter element 20 from the retainer. Moreover, the relationship of the friction grip 30 and second letter element 21 is established by the pins 34. The bail 29 and eccentric lock 30 are structurally related so that with the bail 29 extended parallel to the face plates 22 of the letter elements, the grip lock 30 will be directed 25 toward and be disposed adjacent to the back surface of the face plate 22 of the second letter element 21.

In accordance with the operation and utility of the buckle the end of the belt equipped with snaps or the like is threaded through and engaged with the bail 29. The opposite or free end of the belt may then be inserted into the opposite end of the buckle, i. e., between the front section 16 of the retainer and the back surface of the face plates 22, the edges of the belt being confined between the forwardly directed flanges 18 of the retainer. In order to facilitate projection of the belt end completely through the buckle the tubular member 28 is turned axially so as to swing the bail 29 rearwardly, displacing the eccentric ribbed grip 30 from the path of the belt end. With the end of the belt then projected between the eccentric grip 30 and the face plate 22 of the second letter element 21, the bail is returned into parallel relationship with the face plates. This operation is effective to swing the friction lock 30 against the belt end and clamp the same against the face plate 22 of the second letter element 21.

The end of the belt engaged by the eccentric 30 will thus provide a complete background for the letters of both elements, being visible, in the illustrated embodiment, through the center of the "O" and between the diverging sections of the "K," while hiding completely the retainer 15 and

belt engaging device with the exception of the extreme outer corners of the bail 29.

By removing the pins 34 any letter elements may be substituted for those shown and may be arranged in any order desired, each letter element being identical except with regard to the contour of the face plate 22, which may be in the form of any letter of the alphabet. Correspondingly, it will be understood that the letter contours of the face plates 22 are merely illustrative of any desired ornamental configuration.

Moreover, while I have illustrated and described only a single embodiment of my invention, numerous changes in size, design, shape, number and proportion of the various parts may be made, that the widths of the back panel 23, flanges 24 and rails 25 of the letter elements may be reduced to the width of the face plate 22 so as to permit the face plates of the letter elements 20 and 21 to contact one another upon assembly, that any conventional type of pin mechanism for pivoting the parts together may be substituted for that shown, that the flanges 18 of the retainer may be omitted, if desired, and that the positions of the eyes 19 and 27 of the retainer and letter elements may be variously changed to locate the eccentric belt-locking device in direct opposition, throughout its length, to the face plate of the second letter element 21, all without departing from the spirit of my invention as defined by the appended claims.

What I claim and desire to secure by Letters Patent is:

1. In a belt buckle, a rear retainer member comprised of a strip of material doubled over so as to include a bight portion joining front and rear reaches, a pair of interchangeable box-like display elements, each display element comprising a face plate, a back member and flanges interconnecting the upper and lower edges, respectively, of said face plate and back member to maintain the latter plate and member in parallel, spaced relationship, the front reach having flanges extending therefrom at the upper and lower edges thereof, said pair of box-like display elements being engaged on said front reach so as to define a through passageway with one of said display elements having the side edge of its back member engaged against the bight portion joining the two reaches, the second display element being abutted against said first display element, and belt attaching and gripping means interconnecting the second display element and the rear reach of the retainer member and constituting means to which one end of a belt can be attached and means for grippingly clamping the free end of a belt against the face plate of said second display element.

2. In a belt buckle, a rear retainer member comprised of a strip of material doubled over so as to include a bight portion joining front and rear reaches, the front reach being of a length sufficient to receive at least one display element thereon, at least one interchangeable display element of box-like form, each display element comprising a face plate, a back member and flanges interconnecting the upper and lower edges, respectively, of said face plate and back member to maintain the latter plate and member in parallel, spaced relationship, said front reach having flanges extending therefrom at the upper and lower edges thereof, each display element being engaged on said front reach so as to define a through passageway, and belt attaching and gripping means interconnecting the end of

the display element remote from said bight portion and one of the reaches of the retainer member and constituting means to which one end of a belt can be attached and means for grippingly clamping the free end of a belt against the juxtaposed face plate.

3. In a belt buckle, a rear retainer member comprised of a strip of material doubled over so as to include a bight portion joining front and rear reaches, the front reach being of a length sufficient to receive at least one display element thereon, at least one interchangeable display element of box-like form, each display element comprising a face plate, a back member and flanges interconnecting the upper and lower edges, respectively, of said face plate and back member to maintain the latter plate and member in parallel, spaced relationship, said front reach having flanges extending therefrom at the upper and lower edges thereof, each display element being engaged on said front reach so as to define a through passageway, each display element having rearwardly extending eyes and said rear reach having a pair of eyes adapted to be aligned with the eyes of said display element, and belt attaching and gripping means having at least one pin engaged in the eyes on said display element and said rear reach to interconnect the display element with the retainer and provide a support for the last recited means, said last recited means constituting means to which one end of a belt can be attached and means for grippingly clamping the free end of a belt against the juxtaposed face plate.

4. In a belt buckle, a rear retainer member comprised of a strip of material doubled over so as to include a bight portion joining front and rear reaches, the front reach being of a length sufficient to receive at least one display element thereon, at least one interchangeable display element of box-like form, each display element comprising a face plate, a back member and flanges interconnecting the upper and lower edges, respectively, of said face plate and back member to maintain the latter plate and member in parallel, spaced relationship, said front reach having flanges extending therefrom at the upper and lower edges thereof, each display element being engaged on said front reach so as to define a through passageway, each display element having rearwardly extending eyes and said rear reach having a pair of eyes adapted to be aligned with the eyes of said display element, and belt attaching and gripping means having a pair of spring pressed pins extending therefrom and removably engaged in the eyes of said display element and said rear reach to interconnect the display element with the retainer and provide a support for the last recited means, said last recited means constituting means to which one end of a belt can be attached and means for grippingly clamping the free end of a belt against the juxtaposed face plate.

5. In a buckle, a retainer comprising a pair of elongated flat sections connected together at one end by a bight portion so as to provide a U-shaped rear member, at least one interchangeable box-like display element comprising a face plate and a back panel connected in spaced relationship at corresponding upper and lower edges, respectively, a belt-engaging member comprising an eccentric friction device and a bail, each display element being telescoped over one of said flat sections of said retainer, and means connecting said retainer, one display element and

said belt-engaging member and pivotally supporting the belt-engaging member in operative relationship with the face plate.

6. In a belt buckle, a rear retainer member of a length sufficient to receive a display element thereon, an interchangeable display element comprising a face plate, and flanges extending from the upper and lower edges of said face plate, said rear retainer member having apertured ears extending therefrom at the upper and lower edge portions thereof, said display element being interchangeably engaged on said rear retainer member so as to define a substantially straight through passageway, said display element having at least one apertured ear 10 adapted to be aligned with said apertured ears, a belt attaching and gripping means having means pivotally mounted in said ears to hold the display element relative to said rear retainer member and constituting means to which one 15

5

end of a belt can be attached and means for grippingly clamping the free end of a belt against the juxtaposed face plate.
